SACCHETTI & WILHELMUS CORP. N.Y.

UNITED STATES PATENT OFFICE.

JOSEPH E. BYRD, OF MOUNT OLIVE, NORTH CAROLINA.

RECEPTACLE.

1,259,208.

Specification of Letters Patent. Patented Mar. 12, 1918.

Application filed May 26, 1917. Serial No. 171,299.

To all whom it may concern:

Be it known that I, JOSEPH E. BYRD, a citizen of the United States, residing at Mount Olive, in the county of Wayne and State of North Carolina, have invented certain new and useful Improvements in Receptacles, of which the following is a specification, reference being had to the accompanying drawings.

10 This invention relates to certain improvements in receptacles and has relation more particularly to a device of this general character especially designed and adapted for use in gathering fruit, vegetables or the like, and it is an object of the invention to provide a novel and improved receptacle wherein a pivoted bottom is employed so that the contents of the bucket may be readily and conveniently discharged without the possibility of the contents of the receptacle being bruised or otherwise injured during the discharging operation.

It is also an object of the invention to provide a device of this general character having novel and improved means whereby the pivoted bottom may be readily and conveniently maintained in applied position and wherein a portion of such means serves as a reinforcement for the bottom.

30 The invention consists in the details of construction and in the combination and arrangement of the several parts of my improved receptacle whereby certain important advantages are attained and the device 35 is rendered simpler, less expensive and otherwise more convenient and advantageous for use, all as will be hereinafter more fully set forth.

The novel features of the invention will 40 hereinafter be definitely claimed.

In order that my invention may be the better understood, I will now proceed to describe the same with reference to the accompanying drawings, wherein—

45 Fig. 1 is a view in elevation illustrating a receptacle constructed in accordance with an embodiment of my invention, a second position of the holding or locking rod being indicated by dotted lines;

50 Fig. 2 is a view in bottom plan of the device as herein disclosed; and

Fig. 3 is a fragmentary sectional view taken substantially on the line 3—3 of Fig. 2.

55 As disclosed in the accompanying drawings my improved receptacle comprises the

body B preferably cylindrical in form and having operatively engaged with its upper portion the handle member H of a conventional type. The opposite end portions of 60 the body B are open and coacting with the lower open end of the body B is the bottom 1 which is adapted to snugly fit within the lower portion of the body B with the under face thereof substantially flush with the 65 lower end of the body B. The bottom 1 is hingedly connected as at 2 with the body B, said hinged connection 2 comprising a hinge member having one leaf 3 thereof extending within the body B while the second leaf 4 70 of the hinge underlies the outer face of the bottom 1. The leaves 3 and 4 are secured to the body B and bottom 1 respectively in any desired manner.

Suitably secured to the outer or under 75 face of the bottom 1 and at opposite sides of the hinge connection 2 are the arcuate members 5 which are positioned in close proximity to the periphery of the bottom 1 and have adjacent extensions outwardly or 80 laterally directed as at 6 to underlie the wall of the body B and whereby the swinging movement of the bottom 1 toward the body B is limited.

The lower portion of the body B substantially diametrically opposite to the hinge connection 2 is provided with the outstanding eye 7 and the upper portion of the body B is provided with a second outstanding eye 8 in longitudinal alignment with the eye 7. 90 Loosely disposed through the aligned eyes 7 and 8 is an elongated rod 9 having one end portion angularly disposed as at 10 and underlying the bottom 1 to hold the same in closed position. The opposite end portion 95 of the rod 9 is also angularly disposed at 11 and it is preferred that the portions 10 and 11 be relatively disposed on an angle of substantially 90°. The straight portion of the rod 9 is of a length less than the 100 length or height of the body B so as to have the angular portion 11 of the rod 9 below the adjacent end of the body B when the extension 10 is in position to be swung to overlie the bottom 1 and vice versa. It will, 105 therefore, be self-evident that in order to cause the extension 10 to operatively engage the bottom 1 the rod 9 can only be rotated in a single direction. When the extension 11 has been swung out of engagement with 110 the bottom 1 the rod 9 may be slightly lifted and turned to cause the extension 11 to over-

lie the adjacent end of the body B whereby it will be perceived that the extension 10 will be held above the lower end of the body B so that the extension 10 will not interfere 5 with the requisite opening or closing movement of the bottom 1.

It is to be understood that the angular extension 6 is so positioned as to slightly obstruct the path of travel of the extension 10 so that said extension is held against accidental outward movement which would tend to release the body 1. It will also be understood that the extension 6 and the adjacent end portion of the member 5 will readily yield to permit the extension 10 to pass therebeyond in either direction when the rod 9 is positively rotated or rocked through the medium of the hand grasp or handle afforded by the extension 11. It is also preferred that the outer or under face of the bottom 1 with which the extension 10 coacts, be provided with a wear plate 12.

My improved receptacle as herein embodied is especially adapted for use in the gathering of fruits, vegetables or the like and after the receptacle has been filled the same is carried to any desired location to be emptied. In emptying the basket it is only necessary that the extension 10 be swung 30 from the bottom 1 and the body B elevated. This operation will result in the bottom 1 assuming an inclined position so that the contents of the receptacle R may be discharged from the receptacle with the possibility of the vegetables, fruit or the like being bruised or otherwise injured, substantially eliminated. It will be further understood that the bottom 1 when in its inclined position will serve as a chute over which the 40 contents of the receptacle will travel so that an abrupt drop of the contents of the receptacle is avoided.

From the foregoing description, it is thought to be obvious that a receptacle constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

60 1. In combination with a receptacle and a swinging bottom therefor, a rod disposed longitudinally of the receptacle and mount-

ed for rocking movement and capable of longitudinal movement, the opposite end portions of said rod being angularly disposed, the angular portion of one end of the rod being adapted to overlie the bottom for holding the same in closed position, the angular portion of the opposite end of the rod serving as an operating means for the rod 65 and also adapted to overlie the adjacent end of the receptacle, the length of the rod intermediate the angular extremities thereof being less than the length of the receptacle.

2. In combination with a receptacle and a swinging bottom therefor, a rod disposed longitudinally of the receptacle and mounted for rocking movement and capable of longitudinal movement, the opposite end portions of said rod being angularly disposed, the angular portion of one end of the rod being adapted to overlie the bottom for holding the same in closed position, the angular portion of the opposite end of the rod serving as an operating means for the rod 70 and also adapted to overlie the adjacent end of the receptacle, the length of the rod intermediate the angular extremities thereof being less than the length of the receptacle.

3. In combination with a receptacle and a swinging bottom therefor, a rod disposed longitudinally of the receptacle and mounted for rocking movement and capable of longitudinal movement, the opposite end portions of said rod being angularly disposed, the angular portion of one end of the rod being adapted to overlie the bottom for holding the same in closed position, the angular portion of the opposite end of the rod serving as an operating means for the rod 80 and also adapted to overlie the adjacent end of the receptacle, the length of the rod intermediate the angular extremities thereof being less than the length of the receptacle, the extremities at the opposite ends of the 90 rods being arranged at an angle of substantially 90°.

3. In combination with a receptacle and a swinging bottom therefor, a rod disposed longitudinally of the receptacle and mounted for rocking movement and capable of longitudinal movement, the opposite end portions of said rod being angularly disposed, the angular portion of one end of the rod being adapted to overlie the bottom for holding the same in closed position, the angular portion of the opposite end of the rod serving as an operating means for the rod 95 and also adapted to overlie the adjacent end of the receptacle, the length of the rod intermediate the angular extremities thereof being less than the length of the receptacle, the extremities at the opposite ends of the 100 rods being arranged at an angle of substantially 90°.

In testimony whereof I hereunto affix my signature in the presence of two witnesses 105

JOSEPH E. BYRD.
